APPARATUS FOR THE REDUCTION OF PRESSURE FROM MIXTURES OF LIQUIDS WITH GASES

Franz Kochler and Max Josenhans, Leuna, Germany, assignors to Standard Catalytic Company, a corporation of Delaware

Application July 8, 1938, Serial No. 218,244
In Germany July 29, 1937

10 Claims. (Cl. 137—111)

The present invention relates to improvements in an apparatus for the reduction of pressure from mixtures of liquids with gases.

When liquids under high pressure, in particular those which contain in dispersion more or less solid constituents, are to be reduced from pressure through valves or throttle members, the operation not only results in considerable loss of energy but also causes a great wear of the said members and moreover the properties of the product are impaired by the eddies thus formed so that difficulties may be encountered in the further working up of the same.

In order to make use of the energy set free during the reduction of the pressure on such liquids it has already been proposed to use piston pressure-reduction machines having one or more high pressure cylinders in which the energy of the product reduced from pressure is conveyed by pistons to other products, especially liquid products, which are to be brought to a high pressure. The said troubles readily arise in such machines, however, because in these machines the reduction of pressure takes place in the outlet valve and in part also in the inlet valve.

The said difficulties are avoided for the greater part by carrying out the reduction of pressure of highly compressed liquids in cylinder spaces of power machines in which the energy of the inflowing substances is utilized by plungers by way of crank drive and flywheel, whereby only a part of the substance reduced from pressure is ejected with the aid of the plunger while the remainder is recompressed to approximately the initial pressure of the product before a further part of the same is let in to the cylinder of the pressure-reduction machine.

This method of pressure-reduction has, however, proved unsuitable for reducing the pressure on liquids containing gases, especially when the gas content of the said liquids fluctuates strongly. Because of the nature of their driving mechanism these machines cannot be so constructed that the degree of pressure reduction remains automatically the same with varying gas contents of the liquids.

A further drawback of this known method of working consists in the fact that in the case of a temporary absence of initial product from which pressure is to be reduced, the machines used either remain arrested in the compression stroke shortly before the final position of the plunger or, in the case of under-pressure, in the expansion stroke. In both cases, the machine must always be started again and this consider-

ably aggravates operation. By remaining in the expansion stroke in the case of under-pressure there is the danger of sucking in air and forming explosive mixtures in the case of reducing the pressure on mixtures containing hydrocarbons or hydrogen.

Pressure-reduction apparatus which are coupled with crank drive and flywheel, however, also are attended in operation by great danger because in the case of stoppages in the valves, conduits or the like, which may readily occur especially when reducing the pressure on pasty liquids, high excess pressures may be produced by the flywheel action and these may destroy the machines and conduits.

It has also been proposed for the reduction of pressure on liquids, which may contain solids, to employ piston pressure reduction machines containing several high pressure cylinders in which by means of a piston movable in the pressure reduction cylinder chamber the energy of the products to be reduced in pressure is transferred to a liquid in another cylinder chamber. It has been proposed in this operation to employ two auxiliary liquids one being under high pressure and the other under low pressure. In these known machines working with auxiliary liquids the main aim is to avoid, in cases when the positively controlled inlet and outlet valves stick, that both of said valves are simultaneously open which would lead to a violent breaking through of liquid with consequent damage to the apparatus. These machines are intended to operate in such a manner that a higher pressure set up on a portion of the product reduced in pressure remaining in the cylinder by recompression thereof after the ejection stroke positively opens the inlet valve and prevents the outlet valve from opening.

In the operation and construction of these machines the insight was lacking that during the admittance of material to be reduced in pressure into the pressure reduction cylinder a violent rush into the pressure reduction cylinder of the material causing both an undesirable change of its quality and also erosion more particularly in the inlet valve, must be avoided.

We have now found that all drawbacks of the known apparatus can be avoided by using for the reduction of pressure from mixtures of liquids with gases and, if desired, solid substances which are under high pressure an apparatus which comprises a cylinder having a floating member therein, means for forcing said floating member toward one end of the cylinder, means for conducting the working fluid into the cylinder with-

out substantial loss in pressure against the force exerted by the first named means, this force being slightly less than that of the working fluid acting on the floating member, means for cutting off the supply of said working fluid, means for reducing the force applied to the floating member by said first named means while confining the working fluid within the cylinder thereby reducing the pressure on said confined working fluid, and means for expelling said working fluid at the reduced pressure.

By using this apparatus the reduction of pressure is carried out by bringing the mixture to be reduced from pressure (initial product) without substantial loss in pressure into the cylinder of a pressure reduction machine against a piston pressure produced by a high pressure auxiliary liquid, which pressure is substantially the same or only slightly lower than the pressure to be reduced, until the cylinder has been filled to a predetermined degree, stopping the supply of initial product, reducing the piston pressure by changing over to a low pressure auxiliary liquid whereby the piston continues to move until the desired degree of pressure reduction on the initial product is attained, reversing the direction of movement of the piston and ejecting the material reduced in pressure from the cylinder by the pressure of the low pressure auxiliary liquid until only so much material remains in the cylinder to form a brake fluid, closing the outlet valve, changing over to be high pressure auxiliary liquid thereby bringing the brake fluid to approximately the pressure of the initial product and repeating the cycle of operations.

The brake fluid has approximately the same pressure as that of the initial product when the latter can be admitted into the pressure reduction chamber without a violent rush of material occurring. The pressures of the two fluids should be as nearly as possible the same. The difference in pressure should preferably be less than 10 atmospheres and not exceed 30 atmospheres.

By the recompression of the brake fluid to approximately the same pressure as that of the initial product the otherwise unavoidable erosion of the inlet valve and impairing of the properties of the product are avoided.

The said two auxiliary liquids are usually the same, although where convenient they may also be different.

In the known pressure reduction machines operating with auxiliary liquid the opening and closing of the inlet and outlet valves was only made possible when a control device mechanically actuated by the movements of the piston and provided with a high pressure liquid, allows of the opening or closing of the said valves. Obviously such a machine in which the opening and closing of the inlet and outlet valves is dependent on the positions of the piston, cannot automatically adjust itself to fluctuating contents of gases in the liquids such as always occur in automatically high pressure reactions.

In these machines the insight was lacking that the machine must automatically adjust itself to the continuously changing gas content of the material to be reduced in pressure.

In order to adjust the operation of the machine in accordance with the present invention to the fluctuating gas content of the initial product to be reduced in pressure, it is necessary to make the control of the inlet and outlet valves

dependent on the internal pressures prevailing in the pressure reduction chamber.

Advantageously the valves of the pressure reduction machine are controlled by means of an auxiliary controlling slide. Usually the pressure liquid in the auxiliary controlling slide is the high pressure auxiliary liquid. Advantageously the proper sequence of valve controls, necessary for the pressure reduction is effected by the dam pressure of the controlling liquid issuing from the hydraulically controlled valves and by the internal pressure in the pressure release machine in co-operation with check valves.

How the invention may be carried out in practice will be further described with reference to the accompanying drawings which show examples of apparatus in accordance with this invention but the invention is not restricted to the particular examples shown.

20 Figure 1 is a diagrammatic view of a pressure reduction cylinder.

Figure 2 is a diagrammatic view of a flow control system for the cylinder.

25 Figures 3, 4, 5, and 6 show the cylinder and flow control system under different operating conditions.

On one side of the cylinder there is situated an inlet valve A and an outlet valve B for the product to be reduced from pressure. The other side of the cylinder acts as a pump. The valves D and F are normal check valves in the circuits of which the valves C and E are interposed as controlled valves. The diameter of the piston rod is so dimensioned that the surface of the

30 piston diminished by the cross-section of the piston rod brings an auxiliary liquid introduced above the same through the valves C and D to a pressure about 10 per cent higher than the original pressure of the initial product acting on the other side of the piston. It is very desirable that the high pressure auxiliary liquid should have a higher pressure than that of the material to be reduced in pressure because thereby a good lubrication of piston K is attained.

35 This is of particular importance in the pressure reduction of liquids containing solid material in suspension since the higher pressure of the auxiliary liquid prevents solid matter from pressing itself in between the surface of the chamber and the piston wall. The pressure reduction cylinder in accordance with the present invention is preferably upright. This is particularly desirable in pressure reduction of liquids containing solids of

40 higher specific gravity than that of the liquid since then the bulk of the solids sinks to the bottom of the cylinder and does not disturb the movement of the piston. Furthermore in an upright cylinder it is easier to assure that liquid is present to act as the brake fluid.

45 Through the valve C, which is constructed as a controllable check valve, and the check valve D there flows into the cylinder a liquid under low pressure which forces the piston downwards with opened outlet valve B (see Figure 6). Shortly

50 before the final position of the piston, the outlet valve B is closed. The controllable check valve E is then opened, with the result that from the conduit connected thereto a liquid under a pressure about 10 per cent higher than that on the product to be reduced from pressure flows into the cylinder, and the said liquid produces a high counter-pressure on the pump side (see Figure 3). There is no difficulty in constructing the cylinder bottom and the piston so that even in the case

of products containing large amounts of gas there remains in the cylinder a residue of liquid mixture after each ejection of the pressure-reduced product and after closure of the outlet valve B which serves as a brake liquid for braking the piston and for rapidly obtaining the necessary counter-pressure between piston and inlet valve. If it is desired to eliminate the liquid product completely after each stroke and to employ gas as the brake fluid, this may be attained simply by appropriate construction of the piston; cylinder bottom and the arrangement of the outlet valve. In this case also, by the positive and correctly timed closure of the outlet valve B which depends on the position of the piston, the gas remaining beneath the piston is compressed by the high counter-pressure of the liquid above the piston to approximately the pressure of the pressure-reduction product before the inlet valve A. The inlet valve A is then opened, the initial product thus being sluiced into the cylinder without fall in pressure (see Figure 4). The piston is then moved upwards, whereby the liquid situated on the pump side of the piston is moved through the check valves E and F into the high pressure liquid conduit O. When the cylinder has been filled to a predetermined extent, the piston rod actuates a usual control in known manner. The inlet valve A is first closed, whereupon the check valves F and E close and the controllable check valve C is opened, whereupon the initial product is reduced to the lower pressure of the low-pressure liquid in the conduit n while moving the piston upwards again (see Figure 5). Only after attaining this low pressure, which by making the length of the cylinder sufficiently great is always the same even with initial products having varying gas content, is the outlet valve B opened and the product, which is now reduced in pressure, ejected from the cylinder by the liquid flowing in under low pressure through the valves C and D (see Figure 6).

The manner in which the said positive movement is obtained is illustrated in the control diagram in Figure 2.

By the movement of the piston there is effected in known manner the movement of the piston rod of an auxiliary controlling slide S by which a driving agent, which may be taken from the liquid moved through the machine at high pressure, is controlled. The auxiliary controlling slide has five attachments. The pressure liquid enters the slide through the pipe a and passes, according to the position of the piston in the slide, through g or i from the slide into the pressure distributing pipes to the cylinders of the hydraulically controlled valves, in order to flow back after having been reduced from pressure through the two pipes g or i into the slide and to flow away through the pipe f. In the position shown the pressure liquid enters the pipe g from the left-hand section of the cylinder of slide S and returns after reduction from pressure from the controlling cylinders of the valves through the pipe i to the right-hand section of the said cylinder of the controlling slide which it leaves through the pipe f. The connecting pipes between the auxiliary controlling slide S and the cylinders of the controlling pistons b, c, d and e are g and i. Of the groups of pipes g and i there are four branches g₁, g₂, g₃ and g₄ and i₁, i₂, i₃ and i₄ which lead to the controlling cylinders of the hydraulically actuated valves. In the pipes g₂, g₃ and i₂, i₃ there are situated,

directly behind the points where they are branched off from g or i, the throttle valves D₁, D₂, D₃ and D₄ with which the speed of the controlling liquid and consequently the movement of the valves is regulated. In the pipes g₁ and i₁ there are situated the check valves R₁ and R₄ and in the pipes g₂ and i₂ there are interposed the check valves R₂ and R₃, in shunt with the throttle valves D₂ and D₃, which allow unhindered flow of the pressure liquid only in the direction from the controlling slide S to the controlling cylinders of the valves. In the opposite direction, the check valves close, so that for the controlling liquid flowing back from the controlling cylinders of the valves there is only open the way through the throttle valves to the controlling slide. In the pipe i₃, between the outlet from the controlling cylinder d of the valve C and D₁, there is arranged a stop valve V₁ in the form of an overflow valve. On the stem of this valve there is a piston the diameter of which is greater than that of the valve cone. The space in the cylinder which communicates with that face of the piston upon which pressure acts to close the valve is in connection with the part of the pipe i₃ between D₂ and the outlet from the controlling cylinder b of the valve A. In shunt connection with the stop valve V₁ there is situated in the pipe i₃ the check valve R₅, which prevents the direct flow of the controlling liquid from the controlling cylinder d of the valve C through D₁, but allows the flow of the pressure liquid from the controlling slide S through D₁ to d. A second stop valve V₂ is situated in the part of the pipe i₂ between D₂ and the outlet of the controlling cylinder c of the outlet valve B. The space in the cylinder which communicates with that face of the piston of V₂ upon which pressure acts to close the valve is in connection with the pump chamber of the pressure-reduction cylinder Z₁ through line l.

In the pipe g₃, between D₄ and the outlet of the controlling cylinder e of the valve E, there is situated a stop valve V₃ of which the space in the cylinder which communicates with that face of the piston upon which pressure acts to close the valve is connected with the part of the pipe g₂ coming from the outlet of the controlling cylinder c. In shunt with the stop valve V₃ there is situated in the pipe g₃ a check valve R₆ which prevents the direct flow of the controlling cylinder e of the valve E, but which allows the flow of pressure liquid from the controlling slide S through D₄ to e. The stop valve V₄ is situated between D₃ and the outlet of the controlling cylinder b. The space in the cylinder which communicates with that face of the piston of V₄ upon which pressure acts to close the valve is connected with the part of the pipe g₃ which leads to the outlet of the controlling cylinder e and moreover there is situated in the pipe g₁, between V₄ and the outlet of the controlling cylinder b, a stop valve V₅. This stop valve is in the form of a spring-loaded valve which is always held closed by the spring. A smaller piston of this valve is connected by the pipe l with the pump chamber of the pressure-reduction cylinder Z and only presses up the stop valve V₅ at a certain internal pressure of the pump chamber of the cylinder Z.

If the auxiliary controlling slide S be brought into the position shown in Figure 2, the pressure liquid flowing through a and g can firstly enter

through the check valve R_1 into the controlling cylinder b on the side which communicates with that phase of the piston upon which pressure acts to close the valve operated thereby, secondly through the check valve R_3 into the controlling cylinder c on the side of the valve spindle and thirdly into the controlling cylinder d . The liquid situated on the valve spindle side of the controlling cylinder b can escape through the throttle valve D_2 , through i_2 and through the auxiliary controlling slide S to f . The dam pressure formed during the piston movement of the controlling piston before D_2 is conveyed through a pipe to the piston of the stop valve V_1 and holds this at first closed until the stroke of the piston in the controlling cylinder b is ended and the dam pressure in front of D_2 has fallen. Only thereafter can the piston of the controlling cylinder d be set in action by the pressure liquid flowing through g_4 . The liquid situated beneath the piston of d can then flow away through D_1 and through the controlling slide to f . The pressure liquid still remains on the valve spindle side of the controlling cylinder c , the return flow pipe i_1 of which is, however, closed by the stop valve V_2 until the pressure in the pump chamber of the cylinder Z has become so low that the stop action of the piston of V_2 has been removed. The controlling liquid can then flow away through D_2 .

In the position of the auxiliary controlling slide S shown, the following valve movements are accordingly effected positively:

After filling the cylinder Z up to a predetermined level with initial product the inlet valve A is closed, thereupon the controllable check valve C is opened, whereby the product is reduced from pressure down to the low counter-pressure of the filling pipe n . Only after complete reduction of pressure of the product to the low filling pressure of the pipe n can the outlet valve B open, whereby the pressure-reduced product is then forced out from the cylinder Z by the pressing down of the piston K by the low filling pressure from the pipe n .

Shortly before reaching the end of the stroke of the piston K , the auxiliary controlling slide S is reversed in known manner by the piston rod. After this reversing, the pressure liquid flowing in through a and i can firstly enter through the check valve R_2 into the controlling cylinder b on the valve spindle side of the piston and secondly through the check valve R_4 into the controlling cylinder c . The liquid situated on the valve spindle side of the controlling cylinder c escapes through the throttle valve D_3 , through g_2 , through the auxiliary controlling slide S and through f . The dam pressure set up in front of D_3 during the piston movement of the controlling piston c is conveyed to the stop valve V_3 and keeps it closed until the stress of the piston in the controlling cylinder c is completed. Only then can the piston of the controlling cylinder c be set in motion. The dam pressure produced on the valve spindle side of the controlling cylinder c is conveyed to the stop valve V_4 and keeps it closed until the piston of the controlling cylinder c has completed its stroke. Only then is the return pipe from the side of the larger piston surface of the controlling cylinder b set free through V_4 to D_3 . Between V_4 and the outlet of the controlling cylinder b is situated in the pipe g_1 a further stop valve V_5 the spring-loaded piston of which is connected through the pipe l with the pump chamber of the cylinder Z and

which, by its construction, only sets free the return pipe g_1 between the controlling cylinder b and the stop valve V_4 and consequently allows the movement of the piston of the controlling cylinder b when a correspondingly higher pressure is present in the pump portion of the cylinder.

Then the controlling pistons of the controlling slide S are reversed and are situated at the right-hand side, the following valve movements are thus effected:

After ejecting the pressure-reduced product, the outlet valve B is closed, the controllable check valve E is opened so that the pump portion of the cylinder Z is placed under high pressure, and after reaching the desired high counter-pressure above the piston K the inlet valve A is opened and the initial product sluiced into the cylinder Z . The sluiced-in product then moves the piston K until the piston rod again reverses the auxiliary controlling slide S in known manner, whereupon the operations already described are repeated.

The improvements and apparatus herein described and claimed are of particular advantage for the reduction of pressure on the products of hydrogenation or destructive hydrogenation under high pressure, of distillable carbonaceous materials, such as coals of various sorts, tars, mineral oils or products of distillation, conversion or extraction of any of them. The process is in particular beneficial, for the reduction of pressure on the residues containing solid matter withdrawn from the reaction vessel or hot catch-pot in the destructive hydrogenation of coal. The products thus reduced in pressure can be more readily filtered or centrifuged than the products from which pressure has been reduced according to the methods hitherto known.

Pressure reduction of any practical degree may be effected, for example, from 1000 atmospheres or more, 700 atmospheres, 300 atmospheres down to about atmospheric pressure.

What we claim is:

1. An apparatus for reducing the pressure of working fluids which comprises a cylinder having a floating member therein, means for forcing said floating member toward one end of the cylinder, means for conducting the working fluid into the cylinder without substantial loss in pressure against the force exerted by the first named means this force being slightly less than that of the working fluid acting on the floating member, means for cutting off the supply of said working fluid, means for reducing the force applied to the floating member by said first named means while confining the working fluid within the cylinder thereby reducing the pressure on said confined working fluid, and means for expelling said working fluid at the reduced pressure.

2. An apparatus for reducing the pressure of mixtures of liquids and gases which comprises in combination a cylinder having a movable piston therein and valves at each end of said cylinder, means for conducting a high pressure auxiliary liquid having a pressure approximately equal to that of said mixture but only so high that the force acting on the floating member is slightly less than that of the working fluid acting on the other side of the floating member into one end of the cylinder, means for conducting a quantity of the mixture into the other end of the cylinder without substantial loss in pressure against the pressure set up by the auxiliary liq-

uid whereby an equal quantity of high pressure auxiliary liquid is forced out of the cylinder, means for cutting off the supply of said mixture and said high pressure auxiliary liquid, means for reducing the pressure, after the operation of said cutting-off means, of the auxiliary liquid and the mixture while the latter is confined within the cylinder and means for expelling the mixture from the cylinder at the reduced pressure.

3. The apparatus as claimed in claim 2 wherein in the movable piston within the cylinder is guided by a piston rod extending through the end of the cylinder into which the auxiliary liquids are introduced.

4. The apparatus as claimed in claim 2 wherein in the pressure reducing cylinder is in an upright position.

5. The apparatus as claimed in claim 2 in which the means for controlling the valves of the pressure reduction machine are dependent on the pressure within the cylinder.

6. The apparatus as claimed in claim 2 wherein in the pressure reduction machine has an upright cylinder, a piston the rod of which extends through the top of the cylinder and is so dimensioned that the unit pressure of the said high pressure auxiliary liquid introduced above the piston can be higher than the original unit pressure of the mixture while the total pressure of the auxiliary liquid on the piston is less than that of the mixture and the means for controlling

the valves of the pressure reduction machine are dependent on the pressure within the cylinder.

7. The apparatus as claimed in claim 2 wherein in the valves of the pressure reduction machine are controlled by means of an auxiliary controlling slide.

8. The apparatus as claimed in claim 2 wherein in the valves of the pressure reduction machine are controlled by means of an auxiliary controlling slide for which the said high pressure auxiliary liquid is used as pressure liquid.

9. The apparatus as claimed in claim 2 wherein in the proper sequence of valve controls necessary for the pressure reduction is effected by the dam pressure of a controlling liquid issuing from hydraulically controlled valves and by the internal pressure in the pressure reduction cylinder in cooperation with check valves.

10. The apparatus as claimed in claim 2 wherein in the valves of the pressure reduction machine are controlled by means of an auxiliary controlling slide, for which the said high pressure auxiliary liquid is used as pressure liquid, the proper sequence of valve controls necessary for the pressure reduction is effected by the dam pressure of a controlling liquid issuing from hydraulically controlled valves and by the internal pressure in the pressure release cylinder in cooperation with check valves.
